UNITED STATES PATENT OFFICE.

JOHN BERGSTEN, OF HERMOSA BEACH, CALIFORNIA.

WELL ELEVATOR.

Application filed February 4, 1924. Serial No. 690,346.

To all whom it may concern:

Be it known that I, JOHN BERGSTEN, a citizen of the United States, residing at Hermosa Beach, in the county of Los Angeles and State of California, have invented new and useful Improvements in Well Elevators, of which the following is a specification.

This invention relates to elevators, and particularly well elevators such as used for handling casing, tubing and the like in an oil well derrick. Elevators of this type have loads of great weight imposed upon the same and sometimes when lifting casing the casing will swing and in some manner the gate of such elevator may swing open dropping the casing with disastrous results to the flooring of the derrick. The present invention has for an object the provision of an elevator which cannot become unlocked when once locked without the operator intentionally performing such unlatching or unlocking operation.

As best illustrating the preferred form of elevator, reference is made to the figures of the drawing in which—

Figure 1 is a fragmentary side elevation of the elevator;

Figure 2 a plan view partly in section on the line 2—2 of Figure 1;

Figure 3 is an enlarged detail sectional view on the line 3—3 of Figure 1; and,

Figure 4 is an enlarged fragmentary sectional view on the line 4—4 of Figure 1.

Corresponding parts in all the figures are designated by the same reference characters.

Referring with particularity to the drawing, I have designated the elevator as an entirety by A, of which a and b are jaw members of such elevator. The member a might be considered the body and the member b the gate. However, in the present construction the gate and body are practically identical in form, and it is believed that jaw members best define the parts. The members a and b are hingedly joined as shown at 1 in any preferred manner, and one of such members, the member a is provided with a bore 2. In the showing the members a and b are both curved so that when the two members are cooperating they form a substantial annulus. Both members a and b are provided with lateral extensions c, which extensions include two members spaced apart, as 3 and 4. These extensions

are adapted to have a bail member d associated therewith, such bail member being in two parts or including two members as shown at 5 and 6. The extensions c are diametrically opposite when the members a and b are closed, said closed position being shown in Figure 2 by the full lines. The member b is shouldered as shown at 7 to form what may be termed an extension or tongue 8, such extension acting as a part of locking means designated generally by e. This extension 8 is provided with a nose portion 9 and with a transverse recessed portion 10, and such extension is adapted to be received within the bore 2 of the member a. The member a is provided with an enlarged portion 11, and integrally formed or otherwise associated with such enlarged portion is a handle f which in the showing is substantially U-shaped. The enlarged portion 11 is formed with a bore 12 and likewise formed with a recessed portion 13 in communication with the bore 2. The recessed portion 13 is adapted to confine a bolt 14 and in part a handle member 15 which may be substantially in the form of a T, and which has a part thereof, as 16, passed through the bore 12 and in screw-threaded engagement as shown at 17, with the bolt 14. It is intended that the handle 15 should be totally confined or protected by the handle f, as shown best in Figure 2. The bolt 14 is provided with a beveled nose portion 19. The bolt is normally urged into the bore 2 by means of springs 20 and 21, these springs being held to the bolt and to the extension 11 in any preferred manner. In particular the bolt is formed with recesses as shown at 22 and 23 for reception of ends of such springs 20 and 21, and a wall portion bounding the recess 13 is provided with bores or recesses to confine the opposite ends of the springs. To permit assemblage of the device the enlargement 11 is provided with a screw-threaded portion 24 adapted to receive a nut 25. Thus when the nut is removed the bolt with the springs may be inserted within the recess 13 and the handle member 15 then secured to such bolt at the screw-threaded portion 17. When the jaw members are closed the tongue 8 will enter the bore 2 and the nose 9 of such tongue 8 will contact with the nose 19 of the bolt 14 and force the bolt within the recess 13 until such time as the bolt may move back and be received within the notch or recess

10 of such tongue 8 to lock the members *a* and *b* together. If desired, the member *b* may be provided with an auxiliary handle 30. To unlatch the parts *a* and *b* it is only necessary to grasp the handle *f* so that the fingers of the operator may close upon the part 18, whereupon a closing of the fingers will retract the bolt so that the parts *a* and *b* may be opened or swung apart into the position substantially as shown in Figure 2 by dotted lines. It is of course understood that the operator would force such jaws apart by grasping the handle 30, as well. In this form of elevator it is necessary that the same should not be sustaining any load; otherwise the ball *d* would tend to close the jaws and it would be impossible to very readily swing such jaws apart. To ensure that the ball does not slip from the extensions 3 associated with the jaws I may provide positive retaining means for such ball designated by *g*, and said means may comprise two spaced members 31 and 32 formed with a head portion 33 associated with the members 31 and 32, said members 31 and 32 being pivotally associated with the member 4 through the medium of a pivot bolt 34 passed through aligned openings in such members 31 and 32 and the member 4. The head portion 33 is adapted to carry locking mechanism *h*, and the head 33 is provided with a screw-threaded bore 35 and with a reduced bore 36 in communication therewith, and a bolt 37 is confined within the bore 36, said bolt including a head 39 to which is joined a stem 39, said stem being passed through a cap nut 40 in screw-threaded engagement with the screw-threaded part 35 of the head 33. Confined between the cap nut and the bolt head is a coil spring 41. A finger piece 42 is in screw-threaded engagement with a screw-threaded part of the bolt stem as shown at 43. The extensions 3 associated with the jaws are beveled as shown at 44 and likewise provided with recessed portions 45, and when the members *g* are in the open position shown in Figure 1 by dotted lines and then revolved to what may be termed a closed position, or the full line position of Figure 1, the bolt head 38 will first contact with the beveled portion 44 and force the bolt head within the bore 36 until such time as the bolt head may be received within the recess 45, at which time the member *g* will be securely locked between the extensions 3 and 4. An opposite procedure is used to release the member *g* by pulling upwardly upon the finger-piece 42 to retract the bolt head from the recess 45.

By confining the latch arm 15 within the fixed arm *f* and by likewise having the fixed arm of greater dimension than the latch

arm, it is possible to thoroughly protect the latching arm so that an opening of the jaws cannot be accomplished without the intentional retraction of the latching arm by an operator. The drawing shows that the latching arm is in substantial parallelism with the fixed arm associated with the jaw *a*.

It is obvious that various changes and modifications may be made in practicing the invention, in departure from the particular showing, without departing from the true spirit of the invention.

Having thus disclosed my invention, I claim and desire to secure by Letters Patent:

1. In a device of the character disclosed, a pair of jaws hinged together, one of such jaws being formed with a bore and the other of said jaws being provided with a tongue adapted to be received within such bore when the jaws are closed, and means for locking the jaws closed, said means comprising a bolt adapted to have engagement with the tongue, a handle secured to such bolt, and a fixed handle surrounding the first named handle and totally enclosing the same.

2. Improvements in elevators, including two relatively movable members, one of such members being formed with a projecting handle member, means for locking the relatively movable members closed, including means for releasing such locking means, said handle member enclosing such last named means.

3. Improvements in elevators, including two relatively movable members, one of such members being provided with a tongue and the other of such members being formed with a recess adapted to receive such tongue, a bolt for engagement with the tongue to lock the relatively movable members closed, a handle joined to such bolt, and a second handle associated with one of such relatively movable members enclosing the handle joined with the bolt to protect the same.

4. Improvements in elevators, including two relatively movable members, a fixed handle for each of such relatively movable members and a movable handle confined within one of such fixed handles; such movable handle controlling locking means for the relatively movable members.

5. Improvements in elevators, including two relatively movable members and locking means for such relatively movable members; two handle members, one being received within the other thereof and totally confined thereby, such handle so confined controlling such locking means.

In testimony whereof, I have signed my name to this specification.

JOHN BERGSTEN.
